Primary Examiner — Paula A. Greene(74) *Attorney, Agent, or Firm* — Young & Thompson(57) **CLAIM**

The ornamental design for the earphone, as shown and described.

DESCRIPTION

FIG. 1 is a perspective view of front, bottom and left side of an earphone showing my new design;

FIG. 2 is another perspective view of rear, top and left side thereof;

FIG. 3 is a front view thereof;

FIG. 4 is a rear view thereof;

FIG. 5 is a right side view thereof; a left side view being a mirror image thereof;

FIG. 6 is a top plan view thereof;

FIG. 7 is a bottom plan view thereof; and,

FIG. 8 is a perspective view showing the state that the earpiece was attached thereof.

The portions of the article in broken lines are shown for illustrative purposes only and form no part of the claimed design.

1 Claim, 8 Drawing Sheets(56)
